Atty's.

UNITED STATES PATENT OFFICE.

OLIVER THOMAS, OF LOS ANGELES, CALIFORNIA.

SHOE-BUCKLE-DISPLAY DEVICE.

1,282,652.

Specification of Letters Patent. Patented Oct. 22, 1918.

Application filed January 30, 1918. Serial No. 214,535.

To all whom it may concern:

Be it known that I, OLIVER THOMAS, a subject of the King of Great Britain, residing at Los Angeles, in the county of Los Angeles and State of California, have invented new and useful Improvements in Shoe-Buckle-Display Devices, of which the following is a specification.

My object is to make a device for removably mounting a fancy shoe buckle for display, either on sale or in use.

Figure 1 is a perspective showing a shoe buckle displayed in accordance with the principles of my invention upon a pump and dummy foot, and suitable for placing in a store window and the like.

Fig. 2 is a perspective of the buckle and attaching mechanism as used to produce the effect in Fig. 1.

Fig. 3 is a perspective from the rear side of the buckle, the other parts being omitted.

Fig. 4 is a perspective of the retainer for holding the buckle in place upon the pump and dummy foot shown in Fig. 1.

Fig. 5 is a perspective of the backing against which the buckle is displayed.

Fig. 6 is an enlarged sectional detail on the line 6—6 of Fig. 1.

Fig. 7 is a perspective of a retainer to be mounted in a pump and having a snap fastener to receive the buckle.

Fig. 8 is a perspective of the buckle to be used upon the retainer shown in Fig. 7.

Fig. 9 is a vertical central section analogous to Fig. 6 and showing the retainer shown in Fig. 7, the backing shown in Fig. 5 and the buckle shown in Fig. 8, assembled for use.

The retainer 1 shown in Fig. 4 is formed of sheet metal and comprises a lower portion 2, which is substantially circular in elevation and curved in cross-section, to be inserted between the dummy foot 3 and the material of the pump 4, and the upper portion 5 which is circular in plan and curved in cross-section, to fit the dummy foot 3 above the edge of the pump, the portions 2 and 5 being slightly bent on the line 6. A hook 7 is formed of sheet metal bent upon itself to substantially a U-shape and secured in place by rivet 8, the rivet 8 being inserted through one leg of the hook at the approximate center of the portion 5. The backing 9 shown in Fig. 5 is formed of leather, substantially rectangular in plan, and has straight ends 10 and 11 and outwardly bulging

sides 12 and 13. The display buckle 14 shown in Fig. 3 is a fancy buckle, rectangular in plan, curved in cross-section and has a central opening 15. A U-shaped bar 16 is placed across the opening 15 and has out-turned ends 17 and 18 riveted to the side bars of the buckle.

When it is desired to display the buckle 14 for sale, the retainer 1 is placed in position with the portion 2 extending between the dummy foot 3 and the material of the pump 4 and the portion 5 extending upwardly above the edge of the pump and fitting against the instep of the foot. The buckle 14 is placed in position with the bar 16 in the hook 7 and the backing 9 is inserted to cover the opening 15 and hide the hook 7 and bar 16.

The buckle 19 shown in Fig. 8 is intended to be delivered to the customer when a sale is made, and is a replica of the buckle 14 in front elevation, but has an opening 20 in the bar 16. The retainer 21 shown in Fig. 7 is formed of leather or other suitable material, and comprises the lower portion 22 having perforations 23 and the upper portion 24 carrying the snap fastener 25. The retainer 21 goes along with the buckle 19 when a sale is made, and the retainer 21 is placed inside of the instep of the pump of the person using the buckle, and is secured in place by stitches 26 inserted through the perforations 23 and through the material of the pump, so that the portion 24 will project upwardly and fit against the instep of the wearer, and when it is desired, the buckle 19 is placed in position with the snap fastener 25 entering the opening 20 to hold the buckle in place, in front of the portion 24 of the retainer.

Thus I have produced a display device by which a fancy shoe buckle may be removably mounted in place upon a pump for display on sale or it may be removably mounted in place upon a pump for use and wear.

The retainer shown in Fig. 4 may be used for placing the buckle on sale and for placing the buckle in use, and likewise the retainer shown in Fig. 7 may be used for either purpose.

If the buckle has a smooth back bar 16, as shown in Fig. 3, then the retainer shown in Fig. 4 is required, and if the buckle has a snap fastener opening 20, as shown in Fig. 8, then the corresponding fastening member 25 must be on the retainer, as shown in Fig. 7.

The backing 9 shown in Fig. 5 may be

used for either form of retainer, both for sale purposes and for wear.

Various changes may be made in the details of construction without departing from the spirit of my invention as claimed.

I claim:

1. A shoe buckle display device comprising the combination with a buckle having an opening and a cross-bar, of a retainer 10 adapted to fit the instep of a wearer with a substantial part of the retainer extending downwardly inside of a pump and the remainder of the retainer extending upwardly from the upper edge of the pump, and means 15 for detachably connecting the cross-bar of the buckle to the retainer.
2. A shoe buckle display device comprising the combination with a buckle having an opening and a cross-bar, of a retainer 20 adapted to fit the instep of a wearer with a

substantial part of the retainer extending downwardly inside of a pump and the remainder of the retainer extending upwardly from the upper edge of the pump, means for detachably connecting the cross-bar of the buckle to the retainer, and a backing fitting behind the buckle in front of the cross-bar.

3. In a shoe buckle display device, a retainer adapted to fit the instep of a wearer with a substantial part of the retainer extending downwardly inside of a pump and the remainder of the retainer extending upwardly from the upper edge of the pump, an open buckle, means for detachably connecting the buckle to the retainer, and a backing fitting behind the buckle in front of the retainer.

In testimony whereof I have signed my name to this specification.

OLIVER THOMAS.
